N. BINGER

FLOOR SCRAPER

Filed March 11, 1925

Patented Apr. 10, 1928.

1,665,766

UNITED STATES PATENT OFFICE.

NICKOLAUS BINGER, OF PITTSBURGH, PENNSYLVANIA.

FLOOR SCRAPER.

Application filed March 11, 1925. Serial No. 14,676.

My invention relates to a floor scraper and the primary object thereof is to provide a device of the character stated, in a manner as hereinafter referred to, which is conveniently operable to speedily and thoroughly clean and smooth a floor of all irregularities.

Further objects of the invention are to provide a floor scraper of the type described which is simple in its construction and arrangement, strong, durable and efficient in its use, easily operated, adjustable, positive in its action, and comparatively inexpensive to manufacture.

With these and other objects in view which will appear as the description proceeds, the invention is a floor scraper that embodies the peculiar features of construction and novel arrangement of parts hereinafter described in detail, specifically pointed out in the appended claim, and illustrated in the accompanying drawing, which forms a portion of this specification and wherein like numerals of reference designate corresponding parts throughout the several views and in which:

Figure 1 is a side elevational view of a floor scraper in accordance with my invention.

Figure 2 is a front view thereof with a portion of the frame broken away.

Figure 3 is a longitudinal vertical sectional view of the shoe and associated parts.

Figure 4 is a bottom plan view of the shoe with the frame removed therefrom.

Figures 5 and 6 are respectively front and end views of the planing and scraping blade securing blocks.

Referring in detail to the drawing 1 depicts a tubular frame consisting of an upright member 2, a diagonal member 3, and a horizontal member 4. The latter has its rear end fixedly connected with the upright member 2, adjacent to the upper end thereof, and its forward end is fixedly connected with the diagonal member 3, adjacent to the forward end thereof. The converging lower ends of the upright and diagonal frame members 2 and 3 terminate in a common bearing 4'.

A cross-bar 5, provided with a centrally disposed support 6, is carried at the upper end of the upright frame member 2. The support 6 extends into the upper end of the upright tubular frame member 2 and is adjustable therein by means of a set screw

7 which is threadably mounted in the frame member 2 and engages the support 6 for locking the latter in the adjusted position.

A similarly arranged cross-bar 8, provided with a support 9, is carried in the forward end of the diagonal frame member 3. The support 9 extends into the forward end of the member 3 and is adjustable therein by means of the set screw 10, which latter is threadably mounted in the frame member 3 and engages the support 9 for locking the latter in the adjusted position.

A manually slideable metal stock or shoe 11 is connected with the frame 1 and is substantially rectangular in contour with the forward portions of the side walls 12 thereof converging to provide the reduced forward end 13. The forward portion of the shoe 11 is provided with a top 14 formed with an opening 15, and with a smooth soled bottom 16 formed with a comparatively large opening 17. The rear portion of the shoe 11 is divided from the forward portion thereof by the vertically disposed partition 18.

The top of the shoe 11 is provided with a pair of spaced apertured ears 19 disposed approximately at the longitudinal center of the shoe 11. The ears 19 extend parallel with respect to each other, and the bearing 4' of the frame 1 is positioned and pivotally secured therebetween by means of the pin 20.

An eyebolt 21, having its head pivotally connected, as at 22, to the diagonal frame member 3 adjacent to the rear end thereof, extends through an aperture 23 provided therefor in the top 14 at the forward end of the shoe 11. The eyebolt 21 extends into the shoe 11 and is provided at its lower end with a washer 24 and cotter pin 25 to prevent its disengagement from the shoe 11. A spiral spring 26 is mounted on the eyebolt 21 intermediate of its head and the top 14 of the shoe 11.

The rear portion of the shoe 11 is provided with a rearwardly inclined, transversely disposed plate 27 formed integral with the side walls 12, of the shoe 11. The plate 27 extends from the upper rear end of the wall 12 to adjacent to the rear end of bottom 16, thereby providing a transversely disposed slot 28 between the lower end of the plate 27 and the rear end of the bottom 16.

A forwardly inclined plate 29, of slightly greater width than the width of the shoe 11, is integrally connected at its upper end with

the upper end of the plate 27. The plate 29 projects beyond the rear end of the side walls 12, providing a clearance 30 between the latter and the lower end of the plate 29.

5 The plate 27 is provided with a comparatively heavy base 31 and the lower end edge of the outer face of the plate 27 forms a seat for the planing blade 33. The lower end edge of the inner face of the plate 29 likewise forms a seat for the scraping blade 35.

10 The planing blade 33 is fixedly held in position against its seat by a clamp block 36, and the cutting edge thereof projects through the slot 28. The outer face of the block 36 is formed with a transversely extending groove 37 for the reception of the transversely extending rod 38 which latter has its ends fixed in respective side walls 12, of the shoe 11, adjacent to the outer face of the plate 27.

15 The lower portion of the clamp block 36 is formed to provide the short inner leg 32 and the elongated outer leg 34. The planing blade 33 is positioned in the clamp block 36 between the legs 32 and 34, and projects 20 slightly beyond the lower end of the leg 34. A clamping screw 39 is threadably mounted in the upper end of the block 36 and engages the outer face of the plate 27. As the block 36 is fulcrumed against the rod 38, the ad-

25 justment of the screw 39 in the block 36 will serve to lock the planing blade 33 in position against its seat on the lower end edge of the plate 27, or effect its release therefrom.

30 The scraping blade 35 is securely held 35 against its seat by means of a clamp block 40 which latter is identical in construction to the block 36 above described. The block 40 is likewise fulcrumed against a transversely disposed rod 41 fixed in the side walls 12, of the shoe 11. A clamping screw 42 is threadably mounted in the upper end of the block 40 and engages the inner face 45 of the plate 29. The adjustment of the screw 42 will actuate the clamp block 40 to lock the scraper blade 35 in the operative position against its seat on the lower end edge of the plate 29, or to effect its release therefrom.

35 My improved floor scraper is intended to 50 be operated by two persons, one of whom pulls on the cross bar 8, carried at the forward end of the frame member 3, while the

other pushes and bears down on the cross bar 5, carried on the frame member 2. The action of the eyebolt 21 and associated spring 26 will permit of a cushioned oscillatory movement of the frame 1 with respect to the shoe 11 during the operation of the device and will maintain the shoe 11 in the horizontal position when the latter is removed from the floor. The provision of the bottom opening 17 facilitates the attachment of the washer 24 and cotter pin 25 to the eyebolt 21 within the shoe 11.

60 In practice the shoe 11 is drawn across the floor to be smoothed, the planing blade 33 roughly loosening the material to be removed, the scraping blade 35 scraping the floor to a smooth finish. The scraper blade 35 being of greater width than the planing 65 blade 33 the entire area worked by the latter during the operation of the device will be covered and overlapped by the following scraper blade 35. The scrapings are ejected 70 from the shoe 11 through the clearances 30.

75 The adjustment of the cross bars 5 and 8 allow them to be swung to any position desired in respective frame members 2 and 3, thereby permitting of the operation of the device in close proximity to a wall of a 80 room.

85 By the use of my improved device, a floor may be quickly and efficiently cleaned and freed from all irregularities with comparative ease.

What I claim is:

90 In a floor scraper a manually slideable shoe including a body portion having side walls and a top and bottom, an upstanding partition formed integral with said side walls at the rear ends of said top and bottom, a pair of oppositely extending inclined plates merging into each other at the tops thereof, formed integral with said side walls rearwardly of said partition and one arranged 95 in advance of the other, the forward plate spaced from said partition and the lower part of the rear plate extended and spaced from the rear ends of said sides, and a surface working tool clamped to the forward 100 face of each of said plates.

In testimony whereof I affix my signature.

NICKOLAUS BINGER.
